(57) **CLAIM**

The ornamental design for a headwear beanie, as shown and described.

DESCRIPTION

FIG. 1 is a perspective view of a headwear beanie showing my new design;

FIG. 2 is a right side elevational view thereof;

FIG. 3 is a top plan view thereof;

FIG. 4 is a left side elevational thereof;

FIG. 5 is a bottom plan view thereof;

FIG. 6 is a rear elevational view thereof; and,

FIG. 7 is a front elevational view thereof.

The broken line showing of a woman's ponytail, head, neck and shoulders in FIG. 1 is environmental matter and forms no part of the claimed design.

1 Claim, 4 Drawing SheetsFIG. 6

FIG. 7
